[57] CLAIM

The ornamental design for a handbag, as shown and described.

DESCRIPTION

FIG. 1 is a front perspective view of a handbag showing my new design;

FIG. 2 is a front perspective view thereof, with the top flap shown in a fully opened position;

FIG. 3 is a rear elevational view thereof;

FIG. 4 is a side elevational view thereof, the undisclosed side being a mirror image;

FIG. 5 is a top plan view thereof; and,

FIG. 6 is a bottom plan view thereof.

The broken line shown in all views represents conventional stitching.

FIGS. 3-5 show the extension belt forming part of the handle omitted for ease of illustration only.

FIG. 2

FIG. 1

FIG. 4

FIG. 3

FIG. 5

FIG. 6
